UNITED STATES PATENT OFFICE.

FRANK C. RONK, OF CANTON, OHIO.

REGULATOR-VALVE FOR GAS-BURNERS.

1,178,026.

Specification of Letters Patent.

Patented Apr. 4, 1916.

Application filed October 25, 1915. Serial No. 57,899.

To all whom it may concern:

Be it known that I, FRANK C. RONK, a citizen of the United States, residing at Canton, in the county of Stark and State of Ohio, have invented a new and useful Regulator-Valve for Gas-Burners, of which the following is a specification.

My invention relates to improvements in regulator valves for gas burners in which the supply of gas is regulated by the pressure of steam and is more especially adapted to be used in connection with a gas burner for heating steam radiators and the like.

The object of this invention is to provide a regulator valve by means of which the supply of gas is regulated by the steam pressure and by means of which the supply of gas is automatically cut off when the steam pressure reaches a predetermined point.

Another object is to provide adjustment by which the amount of pressure necessary to cut off the gas supply may be regulated.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

In the accompanying drawings: Figure 1 is a fragmentary sectional view of a portion of a steam radiator and gas burner showing my improved regulator valve in connection therewith. Fig. 2 is an enlarged sectional view of the regulator valve showing the turning valve in the proper position for lighting the burner. Fig. 3 is a similar view showing the turning valve in the "safety" position.

Similar numerals of reference indicate corresponding parts throughout the several figures of the drawings.

Referring more especially to the construction illustrated in the accompanying drawings 1 represents the lower portion of the end section of a steam radiator and 2—2 represent the adjoining sections which are connected in any suitable and well known manner as by the rings 3 which allow communication between all of the sections as

shown. A thimble 4 is screw threaded into the section 1 and a small section of pipe 5 which is connected to the regulator valve is slidably mounted within said thimble, 60 extending into the interior of the radiator at a point above the water line, as shown in Fig. 1 of the drawing. The pipe 5 is connected by an elbow 6 with a short pipe 7 which is screw threaded into the neck 8 65 of the top 9 of the steam chamber casing. The body portion 10 of the steam chamber casing is provided with screw threads around its periphery by means of which an internally screw threaded cap 11 is connected thereto, said cap being provided with an inwardly disposed annular flange 12, which contacts with the shoulder 13 formed upon the top 9, clamping said top upon the body portion of the casing. 75

A flexible diaphragm 14, preferably composed of thin sheet metal is provided with the off-set flange 15 which is seated between the shoulder 16 of the steam chamber casing and the top 9, a gasket 17 preferably 80 being interposed between said flange 15 and the top for the purpose of making a steam tight joint.

A screw threaded extension 18 is provided upon the lower extremity of the 85 casing 10 to which is attached the portion 19 of the valve casing. To the portion 19 of the casing is attached a gas supply pipe 20 by means of a union or elbow 21 as shown; said elbow being connected to the casing by means of the screw threaded extension 22. The supply pipe is connected to the casing by means of the screw threaded extension 22. The supply pipe is connected to any suitable source of supply such as 90 street pipes properly connected to a gasometer or other source of supply, reference being had to the kind of gas employed. A turn-valve 23 is located in the casing 19 and adapted to be operated by means of a handle 100 24, said valve being for the purpose of shutting off the supply of gas to the valve when desired, and for setting the valve in the safety position as will be hereinafter described. 105

A spring chamber 25 is provided in the casing and a concentric cylindrical bore 26 communicates therewith. A needle valve 27 is located through the cylindrical bore 26 and is provided upon its upper extremity 110 with a head 28 which bears against the diaphragm 14. A horizontal partition 29 is

provided within the casing 19 and extends from the side walls of said casing to the turn valve 23 dividing the casing into the upper and lower compartments 30 and 31 respectively. A spring 31' is interposed between the head 28 and the lower wall 32 of the spring chamber and tends to normally hold the needle valve in the position shown in Fig. 2. The conical collar 33 is adjustably mounted upon said needle valve by means of a set screw or its equivalent 34, being seated within the conical aperture 35 formed in the partition 29. The lower extremity of the needle 27 is provided with the usual tapered portion 36 adapted to engage the valve seat 37, the reduced aperture 38 leading from said valve seat to the chamber 39.

A regulating needle valve 40, provided with a screw threaded portion 41 is located through the chamber 39, the screw threaded portion 41 being engaged by the internal screw threads 42 and a stuffing box 43 being located around said screw threaded portion for the purpose of forming an air tight joint. The tapered extremity of the needle 40 is located within the valve seat 44 and the opposite end of said needle valve is provided with a squared head 45 by means of which the needle may be rotated for the purpose of regulating the flow of gas therethrough.

An ordinary mixer 46 is connected upon the neck 47 in any suitable and well known manner and provided with the usual apertures 48 to allow the admission of air. A tube 49 is connected with the mixer and is connected with an ordinary "Bunsen" burner 50.

The operation of the device is as follows: When it is desired to light the burner 50 the turn valve 23 is moved into the position shown in Fig. 2, allowing gas to pass from the supply pipe 20 through said turn valve 45 and into the lower chamber 31 and then through the aperture 38 into the chamber 39 and thence into the burner 50. When the stem pressure has become sufficient to expand the diaphragm 14 against the pressure of the spring 31' sufficiently to move the conical collar 33 carried upon the needle 27 out of engagement with the valve seat 35, the turn valve 23 may be moved into the position shown in Fig. 3 allowing the gas to pass from the supply pipe 20 through said turn valve and into the chamber 30 and thence through the aperture 35 to the chamber 31 through the aperture 38 to the chamber 39 and thence to the burner. As the steam pressure increases to a point where it is necessary to cut off the burner the diaphragm 14 will be further expanded, seating the needle point 36 within the valve seat 37, thus shutting off the supply of gas to the burner and causing the light in the

burner to be extinguished. There will then be no chance of gas escaping to the burner after the same has been extinguished, the needle point 36 controlling the admission of the gas to the burner and as the steam pressure becomes lower the spring 31' will move the diaphragm back into the normal position, again seating the frusto-conical collar within the aperture 35, thus preventing the gas from passing from the chamber 30. If the turn-valve 23 should be left in the position shown in Fig. 2, the diaphragm will resume the normal position after the steam pressure has been reduced, thus again moving the needle valve 27 in the position shown in said figure and allowing gas to escape to the burner, which is at this time extinguished. The object of this invention is to prevent accidents happening from circumstances such as the above.

Although the drawings and above specification disclose the best mode in which I have contemplated embodying my invention I desire to be not limited to the details of such disclosure, for, in the further practical application of my invention, many changes in form and construction may be made, as circumstances require or experience suggests, without departing from the spirit of the invention, within the scope of the appended claims.

I claim:—

1. In a device of the character described, the combination of a casing, a steam chamber located within said casing, a flexible diaphragm located within said steam chamber, a gas chamber located in said casing, a partition provided with a conical valve seat and dividing said gas chamber into two separate compartments, one of said compartments being provided with a gas outlet, a needle valve located through said valve seat and arranged to engage said gas outlet, means for holding said needle in engagement with said diaphragm, a frusto-conical valve carried by said needle and arranged to engage said valve seat, a gas inlet passage located within said casing and means for connecting said inlet passage with either of said compartments.

2. In a device of the character described, the combination of a casing, a steam chamber located within said casing, a flexible diaphragm located within said steam chamber, a gas chamber located within said casing, a partition provided with a conical valve seat and dividing said gas chamber into two separate compartments, one of said compartments being provided with a gas outlet, a conical valve seat provided in said gas outlet, a needle valve located within said casing and through the valve seat in said partition, and arranged to engage the valve seat in said gas outlet, a head formed upon the needle valve and adapted to contact with

said flexible diaphragm, a spring adapted to hold said head in engagement with said diaphragm, a frusto-conical valve adjustably mounted upon said needle and arranged 5 to engage the valve seat in said partition, a gas inlet passage located within said casing and communicating with said gas chamber and a turn valve located within said gas

inlet passage, said turn valve provided with a channel whereby the rotation of said turn valve will connect said inlet passage with either of said compartments as desired. 10

In testimony that I claim the above, I have hereunto subscribed my name.

FRANK C. RONK.
